UNITED STATES PATENT OFFICE.

ERNST H. WAHLERT, OF ST. LOUIS, MISSOURI.

DEVICE FOR GRINDING AND POLISHING ROLLS.

Application filed July 7, 1922. Serial No. 573,390.

To all whom it may concern:

Be it known that I, ERNST H. WAHLERT, a citizen of the United States of America, a resident of the city of St. Louis, in the 5 State of Missouri, have invented certain new and useful Improvements in Devices for Grinding and Polishing Rolls, of which the following is a full, clear, and exact description, reference being had to the accompanying 10 drawings, forming a part of this specification.

This invention relates to improvements in devices for grinding and polishing rolls, and particularly to a device for grinding and 15 polishing rolls such as are used in rolling mills for rolling sheets and plates.

As is well known, the rolls employed in rolling mills must be maintained at a high temperature in order to insure a perfect 20 rolling surface. Also, such rolls are subjected to severe usage which results in roughening the surface of the rolls and causes pitting. This necessitates a cessation 25 of operations in order to regrind or re-polish the faces of the rolls. The object 30 of this invention is, therefore, to provide means for grinding and polishing the rolls of sheet rolling mills and for maintaining the surfaces thereof parallel and free from 35 pits and adhering particles without having to shut down the mill with the consequent loss of time and the useless dissipation of heat of the rolls, thus enabling the rolls to be utilized at all times to their greatest rolling capacity.

With the foregoing and other objects in view, the invention comprises the novel construction, combination and arrangement of parts hereinafter more specifically described 40 and illustrated in the accompanying drawings, wherein is shown the preferred embodiment of the invention. However, it is to be understood that the invention comprehends changes, variations and modifications which 45 come within the scope of the claims hereunto appended.

Fig. I is a plan view of my device.

Fig. II is a side elevation of my device 50 in operation, fragments of the mill being shown in section.

Fig. III is a section on line III—III of Fig. II.

Fig. IV is a longitudinal fragmentary section on line IV—IV of Fig. I.

55 Fig. V is a modified form of my grinding and polishing machine.

Fig. VI is a section through the mill showing my device in operation.

In the drawings, A designates the frame of the mill. Journaled in the frame A in 60 suitable bearings in a lower roll B and an upper roll C. The distance between the rolls B and C is regulated by screws D in a well known manner. As is commonly known, the metal in a heated condition is 65 passed between the rolls B and C to flatten the same into sheets and the heat of said metal is, of course, transmitted to the rolls. As a consequence of this fact, said rolls become heated and are maintained at a 70 comparatively high temperature during the rolling operation. The rolls B and C are originally made of such shape so that when the expansion takes place, due to their heated condition, they will attain the shape to efficiently roll the metal into sheets; in other words, the rolling surfaces of the rolls instead of being perfectly parallel with the axis of said rolls are slightly curved, and as 75 said rolls become heated the expansion is 80 sufficient to cause said surfaces to change, so that the surfaces of the lower and upper rolls are exactly parallel. In view of the foregoing, it is of the utmost importance that the grinding and polishing of the rolls 85 to true the surfaces thereof before the final passage of the sheets between said rolls be done very rapidly, because if this is not so the rolls will be permitted to cool slightly whereby their shape will be changed and 90 the final passage of the metal between the rolls B and C will produce a sheet which is 95 not of uniform thickness. The grinding and polishing device which will now be described is designed so that it may be readily inserted between the rolls and the grinding and polishing done very rapidly, thus obviating the objections recited above.

E designates a section of tubing which extends transversely of the mill. The ends 100 of said tubing enter vertical slots F in the frame A of the mill, and said tubing rests on a work supporting table G, which is suitably supported by said mill frame. The section of tubing E is present on several 105 types of mills and will not be described further.

My improved grinding and polishing device comprises a bifurcated supporting member 1, provided with a threaded shank 2 at 110 the rear end thereof. The supporting member 1 is provided with a semicircular trans-

verse pocket 3, which extends transversely of the bifurcated portion of said member, from one leg to the other leg thereof. The semicircular wall 4 of the pocket 3 is provided with a raised portion 5 in which is formed a curved seat 6, the purpose of which will be hereinafter set forth.

Located between the legs of the bifurcated portion of the member 1 is a member 7, said member being provided with an elongated pocket 8 similar to the pocket 3 and a rearwardly extending portion 9. The forward portion of the member 7 is provided with an extension 10 which is adapted to engage the 15 curved seat 6 on the member 1.

11 designates a lever provided with a forwardly extending forked portion 12, the legs of which are provided with elongated slots 13, and a rearwardly extending portion 20 which receives a handle in the form of a section of tubing 14. The lever 11 is pivoted to the member 1 by means of a bolt 15 which passes through the legs of the member 1. Located between the legs of the forked portion 25 of the lever 11 is a curved face 16, the purpose of which will be subsequently pointed out.

30 Located in pockets 3 and 8 are blocks 17 of any suitable abrasive material, said blocks being provided with a blind hole 18 in each of their ends. Extending into each of the blind holes 18 in the blocks 17 is the laterally extending portion of an L-shaped bolt 19, said L-shaped bolts each being provided 35 with an upwardly extending portion which passes through the curved walls of the pockets 3 and 8. The upper portion of each of said L-shaped bolts receives a nut 20 which is screwed downwardly until same bears 40 against the outside face of the curved walls of said pockets whereby said bolts are drawn upwardly, thus causing said abrasive blocks to be drawn tightly against the inside faces 45 of the pockets and firmly held in place in said pockets. As an additional means for holding the abrasive blocks in place, said blocks may be spaced apart from the inside faces of the pockets by ribs 21 and Babbitt or other soft metal poured into said space.

50 Located immediately above the section of tubing E is a member 22 which is provided with an elongated semicircular portion 23 adapted to embrace said section of tubing and a lug portion 24, provided with an internally threaded opening 25, into which the threaded shank 2 of the member 1 is screwed.

The operation of my device is as follows:

55 Assuming that it is desired to grind and polish the rolls, the handle 14 will be raised upwardly relative to the threaded shank 2 of the member 1 whereby the member 7 will be drawn downwardly by the slotted portion 60 of the pivoted lever 11, as shown by dotted lines in Fig. II, whereby the forward end 65 of the grinding device may be inserted be-

tween the rolls B and C. The semicircular portion 23 of the member 22 is then caused to engage the section of tubing E as shown in Fig. II, after which the handle 14 is lowered, thereby causing the member 7 to move upwardly, thus bringing the abrasive block, forming a part of the member 7, into contact with the roll C. When the device is in operation the curved face 16 formed on the pivoted lever 11 bears against the adjacent end of the member 7, thereby keeping the abrasive block in firm contact with the roll. Each of the abrasive blocks 17 is self-adjustable as the threaded shank 2 may oscillate in the threaded opening 25 to compensate for any irregularities in the roll B, while the extension 10 contacting with the curved seat 10' will permit the member 7 to rock slightly, there being sufficient looseness between slots 13 and the bolt 15 to permit 80 said movement.

It is, of course, apparent that the grinding or polishing is started at one end of the roll and after spaces on the rotating rolls B and C the width of the blocks 17 are ground and polished, the device is moved laterally on the tube E at a distance equal to the width of the blocks, when the grinding operation is repeated. The step by step method is continued until the entire roll has been 85 ground and polished.

90 Fig. V illustrates a modified form of my invention wherein the abrasive blocks are provided with supporting pins which are arranged in slots 30' whereby said blocks may move toward or away from the rolls B' and C'. A lever 11' pivoted at 31' bears against portions of the pockets 3' and 8', whereby, when the handle 14' is moved downwardly, 95 said pockets and the abrasive blocks therein 100 will be moved outwardly causing said abrasive blocks to bear firmly against the rolls.

105 By referring to Fig. IV of the drawings it will be apparent that as the abrasive members 17 are worn down by contact with the rolls B and C, the supporting members 1 and 7 may be adjusted toward the rolls to 110 take up said wear by rotating the threaded shank 2 in the lug 24.

I claim:

115 1. A device for grinding and polishing rolls, comprising an abrasive member, a supporting member for holding said abrasive member in contact with a roll, a second abrasive member, said second mentioned abrasive member being supported by said supporting member for said first mentioned abrasive member, and pivoted means whereby said second abrasive member may be moved into contact with a second roll.

120 2. A device for grinding and polishing rolls, comprising an abrasive member, a supporting member for holding said abrasive member in contact with a roll, a second abrasive member, said second mentioned 125 130

- abrasive member being supported by said supporting member for said first mentioned abrasive member, and pivoted means slidably connected to said second abrasive member whereby said second abrasive member may be moved into contact with a second roll.
3. A device for grinding and polishing rolls, comprising an abrasive member, a supporting means for holding said abrasive member in contact with a roll, a second abrasive member, means for holding said second abrasive member, said last mentioned means being supported by the holding means for said first mentioned abrasive member, and pivoted means slidably connected to the last mentioned holding means whereby said second abrasive member may be moved into contact with a second roll.
4. A device for grinding and polishing rolls, comprising an abrasive member, a supporting means for holding said abrasive member in contact with a roll, a second abrasive member, means for holding said second abrasive member, said last mentioned means being supported by the holding means for said first mentioned abrasive member, pivoted means slidably connected to the last mentioned holding means whereby said second abrasive member may be moved into contact with a second roll, and means on said pivoted means for retaining said second abrasive member in contact with said second roll.
5. A device for grinding and polishing rolls, comprising an abrasive member, a supporting means for holding said abrasive member in contact with a roll, a second abrasive member, means for holding said second abrasive member, pivoted means slidably connected to the last mentioned holding means whereby said second abrasive member may be moved into contact with a second roll, and means comprising a curved face contacting with the second holding means whereby said second abrasive member may be retained in contact with said second roll.
6. A device for grinding and polishing the rolls of mills having a transverse tube, comprising an abrasive member, means for holding said abrasive member in contact with a roll, a member embracing said transverse tube for supporting said holding means, a second abrasive member, means for holding said second abrasive member, and pivoted means whereby said second abrasive member may be moved into contact with a second roll.
7. A device for grinding and polishing the rolls of mills having a transverse tube, comprising an abrasive member, means for holding said abrasive member in contact with a roll, a member for supporting said holding means, said member comprising a semicircular portion adapted to embrace said transverse tube, a second abrasive member, means for holding said second abrasive member, and pivoted means whereby said second abrasive member may be moved into contact with a second roll.
8. A device for grinding and polishing the rolls of mills having a transverse tube, comprising an abrasive member, means for holding said abrasive member in contact with a roll, said means being provided with a threaded shank, a member for supporting said holding means, said means having a semicircular portion adapted to embrace said transverse tube and a lug portion provided with a threaded opening into which said threaded shank extends, a second abrasive member, means for holding said second abrasive member, and pivoted means whereby said second abrasive member may be moved into contact with a second roll.
9. A device for grinding and polishing rolls, comprising an abrasive member, means for holding said abrasive member in contact with a roll, a second abrasive member, means for holding said second abrasive member, the last mentioned holding means being supported at one of its ends by the first mentioned holding means and being movable relative thereto, and pivoted means whereby said second abrasive member may be moved into contact with a second roll.
10. A device for grinding and polishing rolls, comprising an abrasive member, means for holding said abrasive member in contact with a roll, a second abrasive member, means for holding said second abrasive member, the first mentioned holding means being provided with a curved seat, an end of said last mentioned holding means being supported in said seat and being rockable therein, and pivoted means whereby said second abrasive member may be moved into contact with a second roll.
11. A device for grinding and polishing rolls, comprising an abrasive member, a supporting member for holding said abrasive member in contact with a roll, said supporting member being provided with a pocket in which said abrasive member is located, a second abrasive member, a second supporting member, said second supporting member being provided with a pocket for the reception of said second abrasive member, means whereby said abrasive members are retained in place within said pockets, and means whereby the second abrasive member may be moved into contact with a second roll.
12. A device for grinding and polishing rolls, comprising an abrasive member, a supporting member for holding said abrasive member in contact with a roll, said supporting member being provided with a pocket

in which said abrasive member is located, a second abrasive member, a second supporting member, said second supporting member being provided with a pocket for the reception of said second abrasive member, means comprising L-shaped bolts whereby said abrasive members are retained in place within said pockets, and means whereby the second abrasive member may be moved into contact with a second roll.

13. A device for grinding and polishing rolls, comprising an abrasive member, a supporting member for holding said abrasive member in contact with a roll, said supporting member being provided with a pocket in which said abrasive member is located, a second abrasive member, a second supporting member, said second supporting member being provided with a pocket for the reception of said second abrasive member, said abrasive members being provided with openings at their ends, means comprising L-shaped bolts, a portion of each of which enters said openings whereby said abrasive members are retained in place within said pockets, and means whereby the second abrasive member may be moved into contact with a second roll.

14. A device for grinding and polishing the rolls of mills having a transverse tube, comprising an abrasive member, means for holding said abrasive member in contact with a roll, said means being provided with a threaded shank, a member for supporting said holding means, said means having a semicircular portion adapted to embrace said transverse tube and a lug portion provided with a threaded opening into which said threaded shank extends, a second abrasive member, a second supporting member movable independently of said first supporting member, said supporting members being provided with pockets within which said abrasive members are located, said abrasive members being provided with openings in their ends, means comprising L-shaped bolts a portion of each of which enters said openings whereby said abrasive members are retained in place within said pockets, and means whereby the second abrasive member may be moved into contact with a second roll.

In testimony that I claim the foregoing I hereunto affix my signature.

ERNST H. WAHLERT.
